WEB FEEDING MECHANISM FOR BAG MACHINES

George W. Poppe, Brooklyn, N. Y., assignor to
Equitable Paper Bag Co., Inc., Brooklyn, N. Y.,
a corporation of New York

Original application September 30, 1932, Serial
No. 635,533. Divided and this application June
21, 1933, Serial No. 676,871

3 Claims. (Cl. 93—18)

This invention relates to a machine for making bags and more particularly to the making of bags from relatively thin material. The improvements, however, are not limited to a machine for handling thin material but possess advantages in the making of bags of ordinary paper.

This application is a division of my application Serial No. 635,533 filed September 30, 1932.

10 An object of the invention is the better control and handling of the bag material both in the web and in the tube. A further object is the production of a more attractive and serviceable bag at minimum cost.

15 A feature of the invention resides in the provision of feeding means engaging the web prior to folding the same into a bag tube with means whereby such feeding means may be rendered ineffective when the machine is being first threaded up.

20 Further features and advantages will become apparent from the following description and claims when taken in connection with the accompanying drawings in which—

25 Figure 1 is a longitudinal section of a bag machine embodying my improvements;

Figure 2 is a plan and part sectional view on the line 2—2, Figure 1;

Figure 3 is a side elevation viewed from the bottom of Figure 2; and

Figure 4 is an enlarged sectional view on the line 4—4, Figure 3.

Referring to the drawings and more particularly to Figures 1 and 2 there is the usual supporting framework 2, the side members of which carry the various shafts for driving the usual mechanism of a bag machine, together with brackets for supporting the various auxiliary structures with which the present invention is more particularly concerned.

Referring to Figure 2, the machine is driven from a motor 4 whose shaft is provided with a pulley 5 about which passes a belt 6 to a pulley 7 on the shaft 8, which carries the lower pinch roller and from which shaft most of the other parts receive their drive. On this shaft is also carried a sprocket wheel over which passes a sprocket chain 10 connected to a sprocket 11 on shaft 12, Figures 2 and 3. A tension roller 13 is provided to keep the sprocket chain sufficiently taut. The shaft 12 carries a gear that meshes with a similar gear on a stud shaft 14. The latter shaft carries a sprocket wheel for engagement with a sprocket chain 15 by which motion is transmitted to shaft 16, the latter shaft carry-

ing dies for making incisions in the paper web in a manner to be later described.

The paper or other material which is to form the bags is fed as a web 18 from a roll 19 supported on a shaft 20 in the lower portion of the rear framework. The web passes over guide rollers 22, 23 and 24 and around another roller 26 which reverses its direction of movement, the latter roller being carried by shaft 27.

5 The mechanism so far described is that which is found in an ordinary bag machine and is of well-known construction. In said machines, however, the roller 26 served merely to reverse the direction of the web but was not itself positively driven.

10 In the present invention one of the features thereof consists in the provision of means for positively driving the roller 26 thereby relieving somewhat the strain on the paper or other bag forming material and permitting thinner and 15 more delicate material to be used to advantage.

20 For positively driving the roller 26 a pulley 28 is secured to the lower end of shaft 12 as viewed in Figure 3, the shaft 27 being provided with a similar pulley 29, the pulleys being connected by 25 a belt 30.

When first setting up the machine the paper is threaded into the machine by hand and it is necessary to give some motion to the parts in order that the web may be properly started. With the 30 roller 26 positively driven this operation would be very difficult unless means were provided to ease up on the belt 30 during the setting-up operation. I have therefore provided variable tension mechanism for this belt constructed as follows: A stud shaft 31 projects from the side frame plate 2 as indicated in Figure 6, said shaft carrying an arm 32 supporting a pulley 33, Figure 3. Between the arm 32 and the side frame plate 2 is interposed a collar 34 and friction washers 35 are provided on either side of the arm and a spring 36 is interposed between a nut 37 and the outside washer. This gives sufficient tension to the arm 32 to hold it in any position to which it is positively moved. Normally the arm is positioned as shown in Figure 3 and the roller 33 is 40 bears on the belt 30 with such pressure as will enable it to drive the roller 26. When, however, the web is being initially threaded through the machine the roller 33 is moved away from the under surface of the belt thereby permitting sufficient slack to allow the roller 26 to turn freely.

45 The paper web after passing over the roller 26 is delivered to mechanism which folds it into the bag tube in the usual manner, such mechanism 50

including a former plate 38, the right end of which, as indicated in Figure 1, is bent upwardly at about 45°. The former is supported from a bridge 40 carried by arms 41 projecting forwardly and upwardly. The web passes under the former and is folded over onto it as illustrated in Figure 2. Projecting upwardly from the side plates 2 are four standards 42 which support two plates 43, Figure 2, the plates being separated sufficiently 10 to permit the bag tube to freely move between them. Adjustment of the plates to and from each other is effected by slotting the plates as shown in Figure 2 and providing set screws to hold them in the proper adjustment. These plates 43 support rollers which aid in giving the necessary 15 control of the folded web and will be referred to later in greater detail.

The folded tube passes to the feed rollers indicated at 44, the upper pair of which are mounted on shaft 45 and the lower pair on shaft 46, these shafts extending into and being supported by the side frames of the machine. Preferably the upper rollers are provided with facings 44a of rubber, leather or other material such as will 20 provide the desired surface friction. The lower rollers are of steel without facings. For driving the feed rollers there is provided a gear 48 on the shaft 8, Figures 2 and 3, which gear meshes with an idler 50 which in turn meshes with a gear 51 on the lower shaft 46. Near its other end but within the frame 2 the shaft 46 carries gear 30 52 meshing with gear 53 on the upper shaft 45. The gears 52 and 53 are of the same size so that the feed rollers rotate in a 1 to 1 ratio.

35 After the web has been formed into a bag tube by being folded over the former and passes between the feed rollers 44 it is severed into a bag length by mechanism including the so-called pinch bars and the striker bar. The pinch bars 40 are also driven from the shaft 8 which has secured to it a pinion 55 meshing with a pinion 56 on the upper shaft 54 which carries the pinch bar 47, the pinions 55 and 56 also driving in a 1 to 1 ratio.

After the severance of the bag tube it passes on to mechanism which closes the bag bottom and this mechanism is of the usual and well-known construction and consists of upper and lower cylinders carrying respectively a tucker blade and clamp, which cylinders are likewise driven from the shaft 8.

From the foregoing it will be observed that the feed rollers are assisted in drawing forward the folded web by the roller 26 which is driven in 10 timed relation with the feed rollers. When, however, the machine is to be initially threaded up the roller 33 is moved from the position shown in Figure 33 so that sufficient slack is produced in the belt 30 to render the machine easily operable 15 by hand.

What I claim is:—

1. In a bag machine the combination with the former about which a web of paper is wrapped to form a bag tube and feed rollers for engaging 20 the tube, of a roller about which the web of paper passes prior to being folded into a tube, means for driving said roller and means for rendering said drive ineffective at will.

2. In a bag machine the combination with the 25 former about which a web of paper is wrapped to form a bag tube and feed rollers for engaging the tube, of a roller about which the web of paper passes prior to being folded into a tube, means including a belt for driving said roller in timed 30 relation with said feed rollers and means for rendering said drive ineffective at will.

3. In a bag machine the combination with the former about which a web of paper is wrapped to form a bag tube and feed rollers for engaging 35 the tube, of a roller about which the web of paper passes prior to being folded into a tube, means including a belt for driving said roller in timed relation with said feed rollers, an adjustable member bearing against said belt and means for holding 40 said member in different adjusted positions.

GEORGE W. POPPE.
